ATT'Y'S:

UNITED STATES PATENT OFFICE.

ALEXANDER WARSHAUER, OF CAMBRIDGE, MASSACHUSETTS.

SHIRT.

1,313,932.

Specification of Letters Patent. Patented Aug. 26, 1919.

Application filed September 27, 1918. Serial No. 255,899.

To all whom it may concern:

Be it known that I, ALEXANDER WARSHAUER, a citizen of the United States, residing at Cambridge, in the county of Middlesex and State of Massachusetts, have invented new and useful Improvements in Shirts, of which the following is a specification.

This invention is embodied in a shirt having 10 a permanent, turn-down-collar, a front collar-button adapted to confine the ends of the permanent collar, said button being exposed for engagement with the end button-holes of a detachable collar, and a tab adapted to 15 support a rear collar-button in position to engage the rear button-hole of a detachable collar, said tab being concealable within the permanent collar when not required for use.

The object of the invention is to enable a 20 shirt to be worn with a negligée effect without a detachable collar, and to be supplemented by a detachable collar when a more formal effect is desired.

Of the accompanying drawings, forming 25 part of this specification:

Figure 1 is a perspective view of a shirt embodying the invention, without a detachable collar.

Fig. 2 is a similar view, showing a 30 detachable collar applied to the shirt.

Fig. 3 is a fragmentary front view of the shirt without a detachable collar.

Fig. 4 is a fragmentary rear view, showing 35 the shirt without a detachable collar, a portion of the back of the permanent collar being broken away to show the tab, as interposed between the neck-band and flap of the permanent collar.

Figs. 5 and 6 are fragmentary rear views 40 of the permanent collar portion of the shirt, showing different adjustments of the tab.

Fig. 7 is a section on line 7—7 of Fig. 5.

Fig. 8 is a section on line 8—8 of Fig. 6.

The same reference characters indicate 45 the same parts in all of the figures.

A shirt embodying the invention includes 50 a neck-band 12, suitably attached to the body of the shirt, a flap 13 stitched to the upper edge of the neck-band, said flap and neck-band constituting a permanent turn-down

collar, the dimensions of the flap being such that it is adapted to be concealed by a detachable collar 14 applied as hereinafter described.

The ends of the neck-band meet and overlap at the front of the shirt, one of said ends being provided with a button-hole 15, adapted to engage a front collar-button 16 connecting the neck-band ends. Said collar-button may be permanently attached to 60 one end of the neck-band, or may be detachably engaged with a button-hole 17 (Fig. 4) coinciding with the button-hole 15. The ends of the flap 13 are fashioned 65 to expose the button 16.

18 represents a tab attached to the lower edge of the neck-band, at the back thereof, and provided with a button-hole 19, adapted to engage a rear collar-button 20, although, if desired, the button 20 may be permanently 70 attached to the tab. When the use of the tab is not required, it may be inserted, as shown by Fig. 7, between the neck-band and the flap 13, the tab being thus concealed 75 when the shirt is worn without a detachable collar.

It will now be seen that a negligée shirt having a turn-down collar is provided, and that said collar may be concealed by a detachable collar 14, the end button-holes of 80 which are engaged with the front button 16, while the rear button-hole is engaged with the rear collar-button 20, the rear tab 18 being withdrawn from within the attached collar and located outside the flap 13, as 85 shown by Fig. 8.

I claim:

A shirt comprising a neck-band the ends of which meet and overlap at the front of the shirt, one of said ends having a button-hole adapted to engage a front collar-button on the other end, a flexible flap permanently attached at one edge only to the upper edge of the neck-band and adapted to be turned down over the outer side of the neck-band, said flap and neck-band constituting an attached turn-down collar formed to permit the engagement of the front collar-button with the ends of a detachable collar, and a tab attached to the lower 100

edge of the neck-band at the back thereof and provided with a button-holes to engage a rear collar-button, said tab being adapted to be turned upward between the neck-band and flap and covered by the latter and to be turned upward outside the flap to hold a rear collar-button in position to en-

gage the rear button-hole of a detachable collar, the tab and a button held thereby being located wholly outside the flap. 10

In testimony whereof I have affixed my signature.

ALEXANDER WARSHAUER.
